Calif., a corporation of California

Application May 22, 1934, Serial No. 726,968

23 Claims. (Cl. 62—170)

The present invention relates to a process and apparatus for separating wax from mineral oils such as from petroleum, its residues or overhead fractions and from wax-containing lubricating oil stocks for the production of lubricating oils of low pour point. The invention more particularly relates to a process and apparatus for chilling wax-containing oils in order to obtain a controlled precipitation of the wax from the wax-containing stocks.

In lubricating stocks, especially those of considerable viscosity range or boiling range, there will normally be present waxes varying widely in characteristics comprising at the one extreme, hard waxes of relatively high melting point, such as, for example, 150° F. and at the other extreme, soft waxes of relatively low melting point, such as, for example, 110° F. Although ordinarily only a small proportion of the total wax content in the lubricating oil stock will consist of hard waxes, their presence in the waxy stock is very important since they have such a low solubility in the solution of waxy oil and diluent and are usually the first type of wax to separate on gradual cooling. Also because of the low initial concentration in the solution such hard waxes are precipitated in a very finely divided form on excessively rapid chilling and also because of their low solubility show little tendency towards resolution of these fine particles and crystal growth. It is, therefore, evident that the most critical temperature range is that in which the initial separation of wax occurs because if an excessive number of nuclei are formed at this time there is little possibility of correcting this situation by subsequent digesting operations. It is an object of my invention to control the formation of nuclei during the initial stages of wax separation so as to prevent formation of an excessive number of such nuclei and to permit further crystal growth on nuclei formed in the early stages of chilling.

In general, crystallization of wax is accomplished by inducing a supersaturated condition in the solution of waxy oil and solvent employed to dilute the oil. This is accomplished either by increasing the concentration of the solute by vaporization or separation of solvent, or by reducing the solubility by cooling, or both. Some investigators have shown there is a narrow range of concentration and a corresponding range of temperature of supersaturation within which free formation of new crystal nuclei will not occur. In this range of supersaturation, crystallization will occur on nuclei already present but formation of new nuclei will occur to only a very lim-

ited extent, if at all. This range of supersaturation is commonly referred to as the metastable range. For purposes of definition, the metastable range of supersaturation is that range of supersaturation within which crystallization occurs on the surfaces of crystals already present and spontaneous formation of new crystal nuclei in large amount does not occur.

As soon as the metastable range of supersaturation is exceeded, however, a so-called labile range of supersaturation is reached in which rapid formation of new crystal nuclei will occur. Thus, the labile range of supersaturation denotes a degree of supersaturation in which spontaneous formation of new crystal nuclei occurs to a very large extent. With a slow rate of chilling, the rate of crystallization upon the wax nuclei already present is sufficiently rapid to relieve the supersaturation and permit crystallization to occur within the metastable range so that uncontrolled formation of new nuclei does not occur. With an excessively rapid rate of chilling, however, the degree of supersaturation exceeds the metastable range and this results in the formation of large numbers of new nuclei and consequent reduction in the average particle size due to the production of a large amount of fine particles which are of a gelatinous or slimy character. A wax slurry of this character is difficult to separate from the oil solvent solution by either settling or filtering. The permissible rate of chilling will, of course, depend not only on the extent of the metastable range but also upon the rate at which supersaturation is relieved by crystallization upon particles of wax already present. It is another object of my invention to control conditions and rate of chilling in dewaxing operations within the metastable range of supersaturation and to relieve supersaturation by crystallization of wax on wax particles already present in the solution.

In one of the known methods for separating wax from oils, the oil is mixed with a hydrocarbon solvent, more particularly a liquefied normally gaseous hydrocarbon solvent, such as liquid propane. The admixture is effected under a pressure sufficient to maintain the solvent in the liquid phase. Thereafter, a portion of the solvent is vaporized under reduced pressure in order to effect chilling and precipitation of wax from solution. In the case of propane, by reducing the pressure down to atmospheric, a temperature of approximately -40° F. may be obtained in the remaining oil and solvent solution. The wax which precipitated during the chilling operation

is then removed by settling, filtering or centrifuging. The remaining propane may then be removed from the dewaxed oil by distillation.

In dewaxing lubricating oils by the use of liquefied normally gaseous hydrocarbons such as propane, it has been found that in batch operation the rate of chilling must be very carefully controlled because when the chilling is accomplished at an excessive rate, a wax slurry is formed which is very difficult to separate from the oil and remaining solvent by such means as settling or filtering. It is usually found undesirable to exceed a chilling rate of about 3° F. per minute in the temperature range from about the temperature at which wax begins to precipitate from solution or the cloud point of the oil solution down to the final dewaxing temperature. However, more rapid chilling may more often be carried out between the temperature ranges of 0° F. and the usual final temperature of about -40° F. Preferably, however, the rate of chilling should not be more than 3° F. per minute from the cloud point of the solution down to the final temperature of -40° F. While such control of chilling rate in bath operations is relatively simple and can be accomplished readily in chilling by internal refrigeration merely by drawing off the propane vapor at a suitably controlled rate so that the pressure of the vapor above the liquid falls at a rate corresponding with the desired rate of reduction of temperature, controlled chilling under the conditions of continuous flow is more difficult to accomplish because it has usually been necessary in the past to employ a definite number of stages with definite pressure differences between each stage. These pressure differences correspond with definite differences in temperature and the tendency is for the temperature of the stream to drop immediately, due to flash vaporization, as soon as the pressure is reduced on passage through the control valve in the line connecting the stages. It is thus another object of my invention to accomplish controlled chilling under conditions of continuous flow and to obtain results similar to controlled vaporization of solvent in batch chilling operations.

Various other objects and features of my invention will become apparent to those skilled in the art from the following description of my invention taken from the drawings.

I have discovered that controlled chilling within the metastable range of supersaturation in a continuous system may be effectively accomplished by employing a plurality of chilling chambers operating at successively lower temperatures and in which the stream of entering solution of waxy oil and solvent to the first chiller and from one chiller to the next succeeding chiller is commingled with a considerable amount of colder recirculated solution from the chiller to which the entering stream is passed. The mixing is, for example, in the ratio of 9 volumes of recirculated solution to one of the entering stream. By rapid mixing and thorough agitation of the entering stream and the recirculated stream, cooling of the entering stream is accomplished by mixing with concurrent reduction of the wax content by dilution rather than by vaporization of propane under reduced pressure, so that the metastable range of supersaturation is not exceeded at any time. Of course, the chillers in the series are maintained at successively lower temperatures by vaporization of propane at successively lower pressures but the actual chilling of the entering

stream is accomplished by mixing with colder recirculated solution.

The combined streams are introduced into the bottom of the respective chillers and as the mixture flows up the chiller, the temperature is reduced by lessening of hydrostatic head at a rate not in excess of about 3° per minute.

The process will be more readily understood by the following description taken from the drawings in which:

Fig. 1 represents a general flow diagram of arrangement of apparatus adapted to carry out my process;

Fig. 2 represents a modification of arrangement of chillers adapted to carry out the process, and

Fig. 3 represents another modification of a series of chillers provided with a schedule of different pumps to prevent breaking down of wax crystals by attrition as will be set forth in detail.

Referring to Fig. 1, a wax-containing oil such as an S. A. E. 40 waxy distillate produced from Santa Fe Springs crude oil is taken from tank 1 and is passed via line 2 to pump 3 which forces the oil through line 4 and heater 5 and then via line 6 into line 7 where it meets a stream of liquefied normally gaseous hydrocarbon solvent such as liquid propane which has been withdrawn from tank 8 via lines 9 and 10 and pump 11. Approximately 4 to 6 volumes of propane are mixed with one volume of the waxy oil. The waxy oil and liquid propane brought together by means of separate pumps are passed through mixer 12 and thence through heat interchanger 14, line 15, and heater 16 where the temperature of the solution is raised to that at which the wax is completely in solution as, for example, 130° F. The mixture then passes via line 17 through heat interchanger 18, line 19 and cooler 20 where the solution is cooled down to a temperature which is definitely above the temperature of the initial separation of wax although preferably the temperature may be reduced to approximately a few degrees above the cloud point of the oil-diluent mixture. Pressure is controlled by means of relief valve 22 on line 21. This valve is employed for the purpose of maintaining sufficient pressure in the heater 16 to prevent flashing in the heater.

The combined stream of oil and propane is then led into the bottom of the first of the series of chillers 23, 23a, 23b and 23c operating at successively lower temperatures. Prior to the introduction of the mixture into the first of the series of chillers, it is commingled with recirculated chilled oil and propane from the top of chiller 23 which is circulated via line 24 by pump 25. The resultant mixture then flows through 26 into the bottom of chiller 23. The temperature in the upper part of this chiller as well as in the succeeding chillers operating at successively lower temperatures is maintained constant by maintaining a constant pressure in the propane vapor leaving them. Recirculation from the chiller is desirably accomplished in the ratio of about 9 volumes of recirculated solution to one volume of the entering solution so that the wax concentration in the mixture entering the chiller does not exceed the metastable range of supersaturation. It will be observed that the combined stream is introduced into the chiller at or near the bottom so that there is little or no evolution of vapor or flashing on entrance of the mixture into the chiller. The height of liquid at the point of introduction will preferably be such that its hydrostatic head is equal to the difference in the vapor pressure of the solution at the temperature of the entering

mixture and at the top when the solution at the top is in equilibrium with propane at the pressure normally maintained in the chiller. On continued circulation, the warm entering mixture will be 5 gradually cooled as it rises in the chiller due to the reduction in hydrostatic head and consequent evolution of vapor in conjunction with a certain amount of mixing by eddy currents. The chiller will be preferably of such size that the volume of 10 the up-flowing stream will be sufficient so that the desired cooling rate of, for example, about 3° F. per minute, will not be exceeded.

Upon reaching the top of the first chiller, the solution flows down through line 30 and valve 31 15 which is actuated by a float control 32 in the first chamber. It will be noted that this valve is located at a low level so that the distance from the valve to the mixer is very short and flashing upon passage through the valve is reduced to a minimum 20 by immediate mixing and consequent cooling of the stream. Upon passage through valve 31 the partially chilled solution is immediately commingled with colder solution from the top 25 of the second chiller 23a circulated via line 24 and pump 25 in exactly the same manner as in the first chilling chamber. The mixture is then introduced into the bottom of the second chiller via line 26. Chilling in chiller 23a is exactly the same as in chiller 23 except that temperature 30 and pressure conditions are lower. Likewise, the operation in the subsequent chillers 23b and 23c is similar to that in the previous chillers. It is apparent that the number of chilling stages provided should be sufficient that the chilled solution 35 leaving the top of the last chiller will be at the desired dewaxing temperature as, for example, -40° F. When the oil being chilled does not contain sufficient propane to accomplish the desired chilling, further quantities may be introduced through lines 38a controlled by valves 39a.

The pressure at the top of each chiller 23, 23a, 23b and 23c is controlled by compressors 35, 35a, 45 35b and 35c. The propane vapors from the various chillers are removed from the chillers via line 33 which pass to compressors 35, 35a, 35b and 35c where the vapors are compressed and then pass into header 34 to cooler 36 where the compressed vapors are liquefied and then pass 50 via line 37 into propane storage tank 8.

The chilled oil and remaining propane solution containing precipitated wax, preferably in the ratio of approximately 3 to 4 volumes of propane to one of the oil and wax, is withdrawn 55 from the top of the last chiller 23c at the preferred temperature of -40° F. via line 40 controlled by float control valve 41 by means of pump 42 which forces the mixture to wax separating devices such as settlers, filters, centrifuges or other mechanical wax separating units. In the drawings, the chilled mass is passed into the vapor tight wax separator or settler 43. Make-up propane at -40° F. may be introduced into the chilled oil via line 44 controlled by valve 45 in order to provide for adequate settling or filtration 60 of the precipitated wax. In order to prevent ebullition or boiling in the wax separator during the wax settling operation, pressure is imposed upon the solution of oil. This is accomplished by maintaining pressure within the separator by pump 42. As the chilled mass in the wax separator remains in a non-ebullient state, the wax settles out and is collected by vanes 46 on shaft 47 which is operated by belt 48 connected 70 to a suitable source of power not shown. The

wax-free oil dissolved in propane is withdrawn from separator 43 via line 49 and is passed into collecting tank 50. The precipitated wax slurry containing propane settling at the bottom of the wax separator 43 is removed through line 51 and 5 pumped by pump 52 into line 53 where it meets a stream of chilled recovered oil and propane from surge tank 54 via line 55 and pump 56. The two streams then pass through line 53 and mixer 57 into settler 58 which is constructed similarly 10 to settler 43 and in which the wax from settler 43 is washed with the dilute oil-propane solution from surge tank 54. Oil and propane separated from the wax slurry is withdrawn via line 59 and passed into collecting tank 50. 15

The once washed wax slurry is withdrawn from the bottom of settler 58 via line 60 by pump 61 which forces the wax slurry through line 62 where it meets a stream of chilled propane at -40° F. coming from chilled propane storage tank 63 via 20 line 64, pump 65, line 67 and valve 68. The mixture then flows through mixing coil 69 into another settler 70 constructed similarly to settlers 43 and 58. In settler 70 the wax from settler 58 is washed with fresh chilled propane and any oil 25 separated is withdrawn together with the chilled propane via line 71 and passed into surge tank 54. As stated previously, this solution containing a small amount of recovered oil is employed 30 to wash the wax slurry from the first settler 43. The countercurrent washing steps may be carried on in as many stages as desired. The chilled propane in tank 63 is produced by withdrawing a portion of the propane under pressure from tank 8 via lines 9 and 12, cooling it in heat interchangers 13 and 14 and passing it into tank 63. The propane in 35 tank 63 is chilled to -40° F. by vaporizing a portion through line 15 and compressor 16 which forces the vaporized propane through line 17, cooler 36, line 37 into propane storage tank 8. 40

The substantially oil-free wax is withdrawn from the bottom of settler 70 via line 80 by pump 81 which forces the wax through line 82, heat interchanger 83, line 84 into high pressure exhauster 85 where vaporized propane under high pressure 45 is withdrawn via line 86 into line 87. Wax in exhauster 85 is continuously recirculated from the bottom into the top of the exhauster via line 88, pump 89, line 90, heater 91 and line 92. The wax or a portion thereof is then passed through valve 50 93, line 94, heater 95, line 96 into the low pressure exhauster 97. Vaporized propane under low pressure is withdrawn via line 98, compressed in compressor 99 and passed into line 87. Wax in low 55 pressure exhauster 97 is recirculated via line 100, pump 101, valve 102, line 94, heater 95 and line 96. Substantially propane-free wax is withdrawn through valve 103 and passed through cooler 104, line 105 into wax storage tank 106 where it is maintained melted by steam circulated through 60 coil 107.

The substantially wax-free oil and propane from collecting tank 50 is withdrawn via line 110 and pumped by pump 111 through line 112, heat interchanger 114, line 115, valve 116 into high 65 pressure exhauster 117 where vaporized propane under high pressure is withdrawn via line 118. The oil in high pressure exhauster 117 is continuously recirculated through line 119, pump 120, line 121, heater 122 and line 123. The oil containing the remaining propane is then passed through valve 124, line 125, heater 126, line 127 into low pressure exhauster 128. Propane and oil from the low pressure exhauster is continuously recirculated through line 129, pump 130, valve 131. 75

line 125, heater 126, line 127 into exhaustor 128. Vaporized propane under low pressure is withdrawn from low pressure exhaustor via line 132 and passed into line 98, compressed in 99 and passed into line 87. Substantially propane-free oil is withdrawn from the low pressure exhaustor via line 129, pump 130, valve 133, line 134 and passed into storage tank 135 which is cooled by cooling coil 136. The propane vaporized from the low and high pressure exhaustors and passing through lines 87 and 118 is passed into lines 137, 11, cooler 36, line 37 into propane storage tank 8.

In the foregoing disclosure, I have described a method for chilling oil to precipitate wax wherein the stream of waxy oil and propane solution after cooling to a temperature slightly above that of initial separation of wax is introduced under conditions of thorough mixing into a much larger stream of propane-oil solution at a considerably lower temperature at which temperature it is saturated but not appreciably supersaturated with wax and carries in suspension wax particles. The relation between the temperatures and volumes of the two streams is preferably such that the increase in temperature of the circulated stream and consequent increase in solubility of wax in the propane solution is substantially sufficient to hold in solution the quantity of wax brought in by the entering stream. In other words, operating conditions will preferably be chosen so that the wax concentration in solution in the combined stream corresponds approximately with the solubility of wax in the solution at the temperature of the combined stream and will certainly be chosen so that any supersaturation will be very minor in extent and within the metastable range.

The amount of recirculation required in each stage for production of a wax slurry containing the wax in coarse crystals so as to be readily removable by settling or filtration will depend primarily upon the number of stages of chilling provided or, in other words, upon the difference in temperature between stages. With a larger number of stages or smaller difference in temperature, less recirculation of liquid will be required. Other factors which influence the amount of recirculation required in any particular case are the extent to which supersaturation is reduced in the circulating stream prior to mixing with the incoming solution and the concentration of wax in the incoming solution as influenced by the amount of dilution of the waxy oil with propane or other diluent. In general, it is necessary in the practice of my invention to choose such conditions of recirculation as will result in the wax concentration in the mixed stream not exceeding the metastable range of supersaturation of wax at the temperature of the stream. The extent of this metastable range of supersaturation will in turn depend upon such factors as the character and quantity of wax in the waxy oil, the concentration of oil in the solution as influencing the solvent power of the propane for wax, and the presence in the solution of colloidal impurities which ordinarily tend to reduce the crystallization rate or modify the crystal habit. Such impurities may be asphaltic bodies naturally present in the waxy stock or materials added for the purpose of controlling crystal habit, of which materials examples are the aromatic hydrocarbons with long side chains often employed as dewaxing aids to produce wax slurry of better filtering or settling characteristics and giving less loss of oil in the filter cake or settling. By dividing the total range of cooling

into an adequate number of steps and by circulating an adequate amount of chilled solution, this is readily accomplished.

The extent of the metastable range of the solution of waxy oil may be readily determined by anyone skilled in the art. For example, the metastable range may be determined by chilling the solution at varying rates and determining the rate at which uncontrolled formation of new nuclei occurs and hence at that rate of chilling, the degree of supersaturation exceeds the metastable range. At some lower rate of chilling where large crystals of wax are formed, the supersaturation will be found not to exceed the metastable range. 15

The four steps shown to chill the oil are possibly not the minimum permissible in all cases but should be sufficient for most cases. For example, when it is desired to chill the oil-propane solution from 90 down to -40° F., the oil-propane solution in line 21 at a temperature of 90° F. and under a pressure of 153 lbs. gauge is mixed with 9 volumes of colder solution at 60° F. recirculated from the first chilling column. The combined mixture will have a temperature of 63° F. when introduced into the bottom of the chiller 23. As the combined stream flows up through the chiller, the lessening of the hydrostatic head permits vaporization of a portion of the propane which cools the oil from 63° F. at the bottom to 60° F. 30 at the top.

The chiller is preferably of such size that the volume of the up-flowing stream will be sufficient so that the desired cooling rate, for example 3° F. per minute, will not be exceeded. It is 35 evident that with a recirculation of 9 volumes of recirculated material to one volume of entering stream and with a temperature differential of 3° F. between the bottom and the top of the chiller, the volume of up-flow should approximately correspond to ten minutes flow of the entering stream. Pressure is maintained at the top of the chiller at about 97 lbs. gauge by operation of compressor 35. The operation of chiller 23a is exactly the same as that in chiller 23 except that it is maintained at a lower temperature level, for example, the mixture withdrawn from the top of the chiller 23 at a temperature of 63° F. is commingled with 9 volumes of recirculated material from chiller 23a at a temperature of 30° F. The combined stream will have a temperature corresponding to 33° F. As the hydrostatic head on the mixture in 23a is reduced, vaporization of propane will gradually reduce the temperature to 30° F. at the top of the 55 chiller.

Pressure is controlled in 23a by compressor 35a which maintains a pressure in the chiller at about 55 lbs. gauge. In chiller 23b material from the top of chiller 23a at 30° F. is commingled with 9 volumes of recirculated material from the top of chiller 23b at a temperature of 0° F. to produce a combined stream at a temperature of 3° F. which is reduced by flowing up through the chiller 23b to 0° F. A pressure of 60 about 27 lbs. gauge is imposed on chiller 23b by means of compressor 35b. In the next chiller, 23c, one volume of 0° F. material from the top of chiller 23b is commingled with 9 volumes of -40° F. material from the top of chiller 23c, 70 producing a combined stream having a temperature of -36° F. which is reduced at the top of the chiller to approximately -40° F. by vaporization of propane at the reduced hydrostatic head. The pressure maintained at the top of 75

chiller 23c corresponds to about 0 lbs. gauge which is controlled by compressor 35c.

In the foregoing description of Fig. 1, I have described a method for chilling the oil by controlling pressure within the metastable range of supersaturation wherein chilled mixture from the top of the chillers is recirculated by withdrawing it from the top of the chillers and mixing it with the entering stream. In Fig. 2, I have shown a modification for accomplishing the above results. It will be observed that Fig. 2 merely represents a series of chilling chambers. However, it will be understood that apparatus for mixing propane with waxy oil and for preparing the mixture prior to introduction into the chilling chambers is similar to that described in Fig. 1. Likewise, the apparatus for separating propane from the separated oil and wax fractions and for recovering propane may be carried on similarly to that described for Fig. 1.

Referring to Fig. 2, it will be observed that each chiller comprises a vertical column as the chillers shown in Fig. 1, except that it is centrally divided by a vertical partition or baffle 27 extending almost to the top of the column which divides the chiller into two sections 28 and 29. At the lower portion of the partition, an injector 38 is provided which permits fluid from section 28 and line 21 to pass into section 29. Injector 38 is provided with baffles 38' in section 29 so that mixing of the two streams is promoted before discharge into section 29. The entering stream of propane and waxy oil from line 21 passing through relief valve 22 passes through the entrance nozzle 39 which is provided with insulating sleeve 39' in order to prevent appreciable cooling of the entering stream by surrounding cold solution and accompanying deposition of wax on the walls of the nozzle. The entering stream is injected into the injector 38 and is commingled with approximately 9 volumes of chilled solution drawn into the injector from section 28. The mixture passing through the injector 38 and baffles 38' is introduced into the lower portion of section 29. As the combined stream flows up section 29, the temperature is lowered approximately 3° by vaporization of propane due to the reduction in hydrostatic head. The mixture overflows over partition wall 27 into chamber 28 where it is recirculated to the injector, part of the solution being withdrawn via line 30. Thus, by providing an injector I may produce circulation of the mixture within the chiller. The agitation must be so thorough and the mixing so rapid that no opportunity is afforded for cooling of the incoming stream by conduction of heat to the circulating stream but the cooling should take place only by actual mixing of the two streams, since otherwise, the supersaturation may readily exceed the metastable range. In practice this mixing may be accomplished more readily by employing multiple jets rather than the simple jet injector shown.

The partially chilled mixture is withdrawn from the bottom of section 28 via line 30 and pump 25 and passes through float control valve 31 into the next chiller. The operation in chiller 23a and in subsequent stages 23b and 23c is exactly the same as in the first chiller 23 except that the chillers are maintained at successively lower temperatures. The temperature and pressure conditions in the chiller will be exactly the same as in the case of external recirculation as in Fig. 1. For example, if it is desired to

chill oil from 90° F. to -40° F., the entering stream at 90° F. under pressure of 153 lbs. gauge is commingled with 9 volumes of 60° material in injector 38, the combined stream having a temperature of 63° which is reduced to 60° at the top of the chamber. A pressure of 97 lbs. gauge is maintained in chiller 23 by compressor 35. Material withdrawn from the bottom of section 28 of chiller 23 at 60° F. is commingled with 9 volumes of 30° F. material in the injector of chiller 23a to produce a combined mixture of 23° F. material which is reduced at the top of the chiller to 30° F. A pressure of 55 lbs. gauge is maintained in chiller 23a by compressor 35a. Likewise, material at 30° F. withdrawn from the bottom of the chiller 23a is commingled with 9 volumes of 0° F. material at the bottom of section 28 of chiller 23b to produce a mixture of 3° F. material in section 29 which is reduced to 0° F. at the top of the chiller. A pressure of 27 lbs. gauge is maintained in chiller 23b by compressor 35b. 0° F. material withdrawn from the bottom of chiller 23b is commingled with 9 volumes of -40° F. material at the bottom of section 28 of chiller 23c to produce a mixture of -36° F. which is reduced at the top of the chiller 23c to -40° F. A pressure of 0 lbs. gauge is maintained in chiller 23c by compressor 35c.

The chilled solution containing precipitated wax is withdrawn from section 28 of the last chiller via line 40 and float control valve 41 and passed to suitable filters, settlers or other mechanical wax separating devices where the precipitated wax is separated from the oil and remaining propane.

Operation of the chillers is best started by filling all of the chillers with the propane-waxy oil solution at a temperature above the temperature of initial separation of wax and then cooling each chiller very slowly by drawing off propane vapors at a controlled rate so that crystallization will occur slowly and relatively large crystals will be formed. After proper temperatures are attained in each chiller, the continuous flow may be started. Under these conditions, the circulating solution in the first chiller, for example, will contain a relatively limited number of nuclei and the tendency will be for crystallization to occur on these nuclei already present rather than for new nuclei to be formed. On continued operation, the nuclei will tend to be carried on in the succeeding chillers and the number of nuclei in suspension in the first chiller will be reduced. However, fortuitous formation of nuclei by local excess chilling or by attrition will keep the proportion of nuclei in suspension at a suitable point. This tends to be self-regulating since if the proportion of nuclei is unduly decreased, the rate at which supersaturation will be relieved will be reduced and there will be a greater tendency for the supersaturation to enter the labile range with formation of additional nuclei. The reduction in the number of nuclei by flowing into succeeding stages is very desirable, as it will tend to promote the formation of larger crystals which will facilitate the subsequent settling or filtering operation.

One of the most essential points for successful operation is the immediate and complete mixing of the two streams, that is, the entering stream and the colder recirculating stream and the avoidance of any appreciable cooling of the entering stream in any manner except by mixing with the circulating stream. Cooling of the entering stream by conduction of heat to the circulating stream or by partial vaporization is par-

ticularly to be avoided. While it is possible that by the use of injector types of mixing devices, mixing can be accomplished so quickly as to prevent appreciable flashing of the entering stream on release of pressure at the entering nozzle or orifice, such avoidance of flashing may at times be difficult to accomplish in practice and in this latter case it is proposed to prevent flashing by maintaining a sufficient pressure upon the combined streams during the mixing operation so that any possibility of flashing is obviated.

The maintenance of a higher pressure at the point of mixing will, of course, necessitate the release of the pressure at a later point in order that vaporization may take place in the chiller at the desired temperature. The release of the pressure by passage through a relief valve or orifice will result in the setting up of shearing stresses in the flowing liquid which may cause appreciable attrition of the wax particles in suspension with consequent formation of additional nuclei and general reduction of particle size of wax. Moreover, the release of the pressure through a valve or orifice will result in dissipation of the energy corresponding with the pressure differential in the form of heat. With the recirculation of, for example, 9 volumes for one volume of entering solution, the energy so dissipated would be appreciable and the heat generated would increase the load on the refrigerating system. In Fig. 3 I have disclosed an arrangement of apparatus wherein the energy corresponding with the pressure drop may be converted back into mechanical energy as by passage of the solution through a positive displacement pump, such as a gear, Kinney, Waterous or reciprocating pump. If desired, the mechanical energy may be converted into electrical energy and the electrical energy may be returned to the line. In this way any undue increase in the refrigeration load is avoided. Moreover, by suitable choice of the type of pump, the breaking down of the wax crystals by attrition is reduced to a minimum.

Referring more particularly to Fig. 3, the waxy oil solution in propane prepared in the manner disclosed in Fig. 1 and passing through line 21 is introduced into injector 150 where it is commingled with colder solution from chiller 23, for example, in the ratio of 9 volumes of recirculated solution to one volume of the entering solution and circulated from chiller 23 via line 24 and circulating pump 25. The mixture then flows through mixing coil 151, and passes through a positive displacement pump 152 from which the combined streams flow through line 153 into section 29 of chiller 23. Chiller 23 is preferably divided into two sections 28 and 29 by vertical baffle 27, the upper portion of the chiller being open to permit flow of liquid from section 29 into section 28. The operation and flow of liquid in chiller 23 is exactly the same as that in the chillers disclosed in Fig. 2 except that the injector in the interior of the chiller is omitted, circulation being accomplished externally in the manner above indicated.

A portion of the chilled solution withdrawn via line 24 is by-passed into line 154 and is picked up by pump 155 which comprises a positive displacement pump, the speed of which is controlled by float control 32. The solution picked up by pump 155 is passed by line 21a into injector 150a where it is commingled with colder solution from section 28a circulating via line 24a and pump 25a. Combined streams pass through mixer 151a, pump 152a, line 153a into section 29a of chiller 23a.

A portion of the chilled solution from section 23a passing through line 24a is by-passed through line 154a to pump 155a controlled by float control 32a which is forced through line 21b to further chilling in a manner similar to that described for chillers 23 and 23a, or it may be passed to wax settling or filtration in order to separate precipitated wax from solution in the manner described for Fig. 1. The pressure at the top of the chillers 23 and 23a is controlled by compressors 35 and 35a. Propane vaporized from the chillers is withdrawn via lines 33 and 33a, compressed in compressors 35 and 35a and passed into manifold 34 from which it may be passed to the propane condenser and recovered in a manner described in Fig. 1.

Thus, in Fig. 3, I have described the method of operation by which all valves with accompanying possibility of attrition of wax crystals is avoided and the flow is controlled by speed control of positive displacement pumps. As stated above, pumps 155 and 155a comprise positive displacement pumps with speed control by a float control device. Pumps 25 and 25a comprise constant-speed centrifugal pumps, preferably of slow speed type and pumps 152 and 152a comprise positive displacement pumps such as gear, Kinney, Waterous or reciprocating pumps which are connected to induction motors which, when over-driven, will return power to the line.

In the above schedule of pump types, instead of employing a constant-speed centrifugal pump in the position indicated, for pumps 25 and 25a, a positive displacement pump with speed control to maintain constant pressure may be substituted therefor, pumps 152, 152a and 155, 155a remaining the same as in the above schedule. It is obvious to those skilled in the art that further modifications could be made in the types of pumps and methods of control without departing from the spirit of the invention.

While I have described the use of liquid propane as the internal refrigerant-diluent, it may be observed that I may employ other liquefied normally gaseous hydrocarbons for this purpose. Such hydrocarbons include methane, ethane, propane, iso-butane, butane or mixtures thereof. These hydrocarbons may be obtained by rectification of casinghead gasoline by the so-called stabilizing method. They are the overhead thus obtained. They are liquefied by compression and cooling in the conventional manner and are drawn off into pressure chambers where they are maintained in the liquid state until they are used.

It is to be understood that the above description is merely illustrative of preferred embodiments of my invention of which many variations may be made by those skilled in the art without departing from the spirit thereof.

I claim:

1. An apparatus for separating wax from oils which comprises means for mixing waxy oil with a liquefied normally gaseous solvent, a plurality of chillers, means connecting said chillers to permit passage of solution from the top to the bottom of successive chillers and means for recirculating chilled solution from the top of said chillers to solution entering the bottom of said chillers.

2. An apparatus as in claim 1 and means to maintain said chillers at successively lower temperatures.

3. An apparatus as in claim 1 and means for

maintaining said chillers at successively lower temperatures and lower pressures.

4. An apparatus for separating wax from oil which comprises a vertical chilling chamber, 5 means to divide the lower portion of said vertical chilling chamber into two compartments, means at the bottom of said chilling chamber to circulate waxy oil from the bottom of one of said compartments to said other compartment and 10 means for mixing waxy oil circulating to the bottom of said other compartment with oil entering said chiller and means for withdrawing oil containing precipitated wax from the bottom of said other compartment.

15 5. An apparatus as in claim 4 in which said means for circulating oil and for mixing entering oil with oil at the bottom of said other compartment comprises an injector.

6. An apparatus for separating wax from oils 20 which comprises a plurality of chillers, a partition dividing the lower portion of each of said chillers into two compartments, an injector positioned at the bottom of said chillers and communicating from one compartment to the other, 25 means for passing oil from said chiller into said injector, means connecting the bottom of said chillers with successive chillers and means for maintaining said successive chillers at successively lower temperatures.

30 7. An apparatus for separating wax from oil which comprises a vertical chiller, means in said chiller to divide the lower portion of said vertical chiller into two vertical compartments, a mixer, means for passing oil from the bottom of one of said compartments to said mixer, means for passing oil to be chilled to said mixer, means for passing the combined streams from said mixer to the bottom of said other compartment and a pump positioned on said last mentioned means.

40 8. An apparatus for separating wax from oil which comprises a vertical chiller, a vertical partition in said chiller, said partition dividing the lower portion of said chiller into two compartments, a mixer, a conduit connecting the bottom of one compartment with said mixer, a conduit connecting said mixer with the bottom of said other compartment, means for passing oil from the bottom of said first mentioned compartment to said mixer and from said mixer to the bottom of said other compartment, said means comprising a pump positioned intermediate said conduit connecting the bottom of said first mentioned compartment with said mixer, means for passing oil to be chilled into said mixer and means on said conduit from said mixer to the bottom of said other compartment to reduce the pressure of the combined stream passing to said other compartment.

9. A process for chilling liquids which comprises mixing the liquid to be chilled with a volatile liquid refrigerant under superatmospheric pressure, commingling said mixture with a sufficient quantity of previously chilled liquid to reduce the temperature of the mixture to be chilled to substantially that of the previously chilled liquid and removing vaporized liquid refrigerant from the combined mixtures.

10. A process as in claim 9 in which the volatile liquid refrigerant is a liquefied normally gaseous hydrocarbon.

11. A process as in claim 9 in which the volatile liquid refrigerant is liquid propane.

12. A process for chilling liquids which comprises mixing the liquid to be chilled with a volatile liquid refrigerant under superatmos-

pheric pressure, passing the mixture into a chilling chamber which is maintained at a lower pressure and at a lower temperature than said mixture, withdrawing chilled liquid from the chilling chamber and mixing it with the mixture to be chilled in sufficient quantities to reduce the temperature of the mixture to be chilled to substantially that of the chilled mixture withdrawn from the chilling chamber and vaporizing a portion of the volatile liquid refrigerant from the chilling chamber to chill the combined mixture.

13. A process as in claim 12 in which the temperature of the combined mixture of liquid to be chilled, volatile liquid refrigerant and chilled liquid withdrawn from the chilling chamber is reduced to the temperature of the withdrawn chilled liquid by lessening the hydrostatic head on said mixture.

14. In a process for dewaxing oils the steps 20 comprising mixing waxy oil with a volatile liquid refrigerant under superatmospheric pressure, commingling said mixture with a sufficient quantity of previously chilled waxy oil to reduce the temperature of the waxy oil to be chilled to substantially that of the previously chilled waxy oil, and vaporizing a portion of the volatile liquid refrigerant from the combined mixtures.

15. In a process for dewaxing oils the steps 30 comprising mixing waxy oil with a volatile liquid refrigerant under superatmospheric pressure, commingling said mixture with a sufficient quantity of previously chilled waxy oil to reduce the temperature of the waxy oil to be chilled to approximately 3° F. higher than the temperature 35 of the previously chilled waxy oil, and vaporizing a portion of the volatile liquid refrigerant from the combined mixtures.

16. A process as in claim 14 in which the volatile liquid refrigerant is a liquefied normally 40 gaseous hydrocarbon.

17. A process as in claim 14 in which the volatile liquid refrigerant is liquid propane.

18. In a process for dewaxing oils the steps 45 comprising mixing waxy oil with a volatile liquid refrigerant under superatmospheric pressure, passing the mixture into the bottom of a chilling chamber which is maintained at a lower pressure and at a lower temperature than said mixture, withdrawing chilled waxy oil and volatile liquid 50 refrigerant from the top of the chilling chamber and mixing said withdrawn mixture with the waxy oil and volatile liquid refrigerant to be chilled in a sufficient quantity to reduce the temperature of the mixture to be chilled to substantially the temperature of the withdrawn chilled mixture and vaporizing a portion of the volatile liquid refrigerant from the combined mixtures.

19. A process as in claim 18 in which the temperature of the combined mixtures is reduced 60 to the temperature of the chilled waxy oil and volatile liquid refrigerant withdrawn from the top of the chilling chamber.

20. In a process for dewaxing oils the steps 65 comprising mixing waxy oil with a volatile liquid refrigerant under superatmospheric pressure, passing said mixture into the bottom of chilling chamber connected in series and maintained at successively lower temperature and pressure levels by vaporization of said volatile liquid refrigerant under reduced pressure, withdrawing chilled mixture from the top of said chilling chambers and commingling said withdrawn mixture with the mixture to be chilled entering the bottom of said chilling chamber, said admix- 70 75

ture being in quantities sufficient to reduce the temperature of the combined mixture to substantially the temperature of the chilled mixture withdrawn from the top of the chilling chambers.

5 21. A process as in claim 20 in which the volatile liquid refrigerant is a liquefied normally gaseous hydrocarbon.

22. In a process for dewaxing oils the steps 10 comprising mixing waxy oil with a volatile liquid refrigerant under superatmospheric pressure, passing said mixture into the bottom of chilling chambers connected in series and maintained at successively lower temperature and pressure levels by vaporization of said volatile liquid refrigerant under reduced pressure, withdrawing chilled mixture from the top of said chilling chambers and commingling said withdrawn mixture with the mixture to be chilled entering the 15 bottom of said chilling chambers said admixture being in quantities sufficient to reduce the temperature of the combined mixture to substantially the temperature of the chilled mixture withdrawn from the top of the chilling chambers, 20 and lowering the temperature of the combined mixture to substantially the temperature of the withdrawn chilled mixture from the top of the 25

chilling chambers by reducing the hydrostatic head on the mixture.

23. In a process for dewaxing oils the steps comprising mixing waxy oil with a volatile liquid refrigerant under superatmospheric pressure, 5 passing said mixture into the bottom of chilling chambers connected in series and maintained at successively lower temperature and pressure levels by vaporization of said volatile liquid refrigerant under reduced pressure, withdrawing 10 chilled mixture from the top of said chilling chambers and commingling said withdrawn mixture with the mixture to be chilled entering the bottom of said chilling chambers, said admixture being in quantities sufficient to reduce the 15 temperature of the combined mixture to approximately 3° F. higher than the temperature of the chilled mixture withdrawn from the top of the chilling chambers and reducing the temperature of the combined mixture to substantially the 20 temperature of the chilled mixture withdrawn from the top of the chilling chambers by lessening the hydrostatic head on the mixture and vaporizing a portion of the volatile liquid refrigerant.

25 DAVID R. MERRILL.
